UNITED STATES PATENT OFFICE.

PAUL A. BANCEL, OF NUTLEY, NEW JERSEY, ASSIGNOR TO INGERSOLL-RAND COMPANY, OF JERSEY CITY, NEW JERSEY, A CORPORATION OF NEW JERSEY.

SURFACE CONDENSER.

Application filed January 8, 1926. Serial No. 80,007.

This invention relates to condensers, but more particularly to a surface condenser having a plurality of cooling units in the form of groups of tubes. The tubes of the several groups are so arranged that the number thereof decreases toward the outlet opening of each unit.

One object of the invention is to prevent the velocity of the vapor and gases from falling below a certain predetermined ratio during their passage through the condenser. Another object is to insure complete condensation and uniform penetration of the vapor by progressively decreasing the steam flow area and by causing the vapor to contact with an increased cooling area immediately prior to the evacuation of the uncondensable gases.

Other objects will be in part obvious and in part pointed out hereinafter.

The invention consists of the combinations of elements, features of construction and arrangement of parts having the general mode of operation substantially as hereinafter described and more particularly pointed out in the appended claims and illustrated in the accompanying drawings, in which

Figure 1 is a transverse sectional view in elevation of a surface condenser taken through Figure 2 on the line 1-1 looking in the direction of the arrows;

Figure 2 is a longitudinal view in elevation partly broken away illustrating the arrangement of the several cooling units;

Figure 3 is a transverse view in elevation partly in section illustrating a modification of the invention and taken through Figure 4 on the line 3-3 looking in the direction of the arrows, and

Figure 4 is a side view in elevation and partly in section of the modification illustrated in Figure 3 illustrating the manner in which the condensate and the spraying liquid are removed from the condenser by separate pumps.

Referring to the drawings and at first more particularly to the preferred modification illustrated in Figures 1 and 2, A indicates a casing having a steam inlet B and a condensate outlet C. Secured to the opposite ends of the casing A are tube sheets D which in this instance support groups of tubes indicated by E and F which form main and secondary cooling units respectively, and convey water from a water head

G at one end of the condenser to a discharge head H at the opposite end of the casing A. The water head G in this instance has a connection J near the upper portion through which water may be introduced from any suitable source of supply. The head H has a connection K near the lower portion through which the water may be discharged from the condenser.

In the present instance the tubes E comprising the main unit are preferably spaced in the usual manner and consist of the usual number in the upper portion of the casing A and decrease in number toward the lower portion of said unit. The spacing of the tubes E in the lower portion of the main cooling unit is preferably similar to that of the upper portion.

In accordance with the present invention, the tubes F which comprise the secondary cooling unit are arranged in inverted V-shaped formation to extend upwardly into the main cooling unit. The tubes F are preferably of the same cross sectional area as the tubes E and are spaced considerably closer than the tubes E so that a greater proportion of cooling area is presented to the vapor and gases passing therethrough.

Suitable means are provided for dividing the main and secondary cooling units. To this end a pair of inclined baffles L and O are arranged longitudinally through the casing A to converge at a point above the secondary cooling unit. At the base of the baffles L and O are formed a plurality of orifices P through which vapor and gases may pass from the main to the secondary cooling unit and also for the purpose of permitting the escape of condensate from the main cooling unit to the outlet C.

In order to provide a passage for the uncondensable gases from the condenser, an outlet opening Q is formed at the top of the secondary unit. A pipe or connection R arranged to register with said outlet opening is adapted to convey such uncondensable gases to a point outside of the casing A. The means for evacuating the gases from the condenser are not shown, but may consist of any well-known and suitable means, such as for instance a steam jet, or a vacuum pump.

In Figures 3 and 4 the casing A is provided with a main condensing unit, similar to that shown in Figures 1 and 2. Similar

ly a pair of converging baffles L and O are arranged within the casing to divide the main condensing unit from the secondary condensing unit R'. The admission of steam 5 into the condenser and the removal of the condensate therefrom as well as the admission and passage of cooling water through the condenser are like that described in connection with the preferred modification.

In this instance the secondary cooling element R' consists of a plurality of tubes designated by S, T, and U. The tubes S and U are preferably supported by the baffles 15 L and O respectively and have a row of spray nozzles V arranged in such a manner that the spray therefrom is directed toward the center of the casing A. The tube T is preferably arranged above the tubes S and 20 U and centrally with respect thereto, and has in this instance two rows of spray nozzles arranged to direct the spray therefrom towards the baffles L and O. In the side of the water head G is formed a suitable opening W to receive a water head X and to 25 which the tubes S, T, and U are connected at one end. The opposite ends of the tubes S, T, and U are preferably each closed by a cap Y.

Although the tubes S, T, and U are shown provided with a separate water head X, it is obvious that they may be so connected that water may be supplied to them directly from the water head G, in which instance the water head X might be eliminated. 35 However, a separate source of water supply may preferably be provided for these tubes.

In order to prevent the intermixing of condensate from the main cooling unit and 40 the spray water in the secondary unit R', a trough Z is arranged longitudinally through said secondary unit R' to receive the spray water from the nozzles V. The trough Z is preferably arranged at sufficient 45 distance above the bottom of the casing A to permit the free passage of condensate therebeneath to the outlet opening C and is of such width that all spray water issuing from the nozzles V will be caught thereby and thus be prevented from mixing 50 with the condensate. The spray water thus caught by the trough Z may be quickly and conveniently removed therefrom by means of a pump b connected thereto as by means of a

connection e. In like manner the condensate 55 may be removed from the casing A by means of a pump d connected to the outlet opening C by means of a suitable connection e.

In this modification the uncondensable 60 gases will be drawn through the outlet opening Q and the connection R by means of a steam jet f or, if desired, by a vacuum pump.

By means of the construction shown in this invention, the inactive zone usually 65 present in condensers of this type has been eliminated and it has been found that the withdrawal of large masses of uncondensed vapor from the condenser along with the uncondensable gases has also been eliminated. 70 A further advantageous feature of this invention is that uniform penetration throughout the entire area of the several cooling units may be obtained.

I claim:

1. A surface condenser comprising a casing having an inlet at the top for steam and a discharge opening at the bottom for condensate, cooling tubes arranged within the casing transverse to the direction of steam 80 flow, a cooling and devaporizing section within the casing for air and uncondensable gases to be withdrawn from the casing, said section being provided with a pair of side walls converging upwardly and a plurality 85 of spray devices within said walls to spray cooling water across the path of vapors and uncondensable gases in said devaporizing section.

2. A surface condenser comprising a casing having an inlet at the top for steam and a discharge opening at the bottom for condensate, cooling tubes arranged within the casing transverse to the direction of steam flow, a cooling and devaporizing section 90 within the casing for air and uncondensable gases to be withdrawn from the casing, said section being provided with a pair of side walls converging upwardly and a plurality 95 of spray devices within said walls to spray cooling water across the path of vapors and uncondensable gases in said devaporizing section, and means to collect 100 water sprayed by said devices separately from the condensate.

In testimony whereof I have signed this specification.

PAUL A. BANCEL.
